UNITED STATES PATENT OFFICE.

RICHARD H. BROWNING, OF ADRIAN, MISSOURI.

CHURN.

SPECIFICATION forming part of Letters Patent No. 374,774, dated December 13, 1887.

Application filed August 22, 1887. Serial No. 247,585. (No model.)

To all whom it may concern:

Be it known that I, RICHARD H. BROWNING, a citizen of the United States, residing at Adrian, in the county of Bates and State of Missouri, have invented a new and useful Improvement in Churns, of which the following is a specification.

My invention relates to improvements in churns; and it consists in a certain novel construction and arrangement of devices, fully set forth hereinafter, and specifically pointed out in the claims.

In the accompanying drawings, Figure 1 is a rear view of the device, showing the churn in section. Fig. 2 is a vertical longitudinal section of the same. Fig. 3 is a detail sectional view showing the manner of securing the driving-wheel and its connections.

Referring by letter to the drawings, A designates the churn, to the upper edges of which at diametrically-opposite points are secured the brackets B B, each of which comprises the socket b and the bent arm b', adapted to engage over the upper edge of the churn-body. 25 b² designates a set-screw passed through an ear on the lower end of the bracket, and adapted to impinge against the side of the churn to hold the bracket in place.

C designates a transverse bar. To the upper side thereof, at the center, is secured the standard D, having bearings d d', respectively, in the upper and lower ends, and the ends of the bar C are provided with longitudinal slots c c and transverse perforations c' c', communicating with the said slots. The series of perforations c' c' in each end of the bar are for a purpose hereinafter explained.

E E are arms depending from the extremities of the bar C, and adapted to be stepped at the lower ends in the sockets of the brackets B on the sides of the churn. The upper ends of the said arms are provided with a series of transverse perforations, e e, adapted to align with the perforations in the extremities of the 45 bar C.

E' represents a bolt adapted to be passed through the said aligned perforations to secure the upper ends of the depending arms E E to the extremities of the bar C. It will be seen that the arms E E are thus hinged to the bar C, so that in applying the churn mechanism to different churns any slight differences

in the sizes thereof will not prevent the stepping of the lower ends of the arms in the sockets of the brackets. The extremities of the 55 bar C are provided with series of perforations to enable the arms E E to be placed at the proper distance apart to suit the width of the churn to which the device is applied, and the upper ends of the arms E are provided with 60 series of perforations to enable the bar C to be raised or lowered, for a purpose hereinafter explained.

G designates a vertical hollow shaft (or tube) mounted in the bearings d d' in the 65 standard D, which shaft extends down to a point near the bottom of the churn A, and is provided on the upper end (above the bearing d) with a gear-wheel, G'. The object in providing means to adjust the bar C vertically 70 will now be readily seen—namely, to enable the lower end of the hollow shaft to be adjusted close to the bottom of the churn, whether the said churn is deep or shallow.

H designates a sleeve surrounding the hollow shaft G, with the upper end thereof close to the lower side of the bar C, and the upper end thereof is provided with a gear-wheel, H'.

I designates a bracket secured to the lower side of the bar C at the center thereof, which 80 passes down under the gear-wheel H' and is provided with a bearing, i, in which operates the sleeve H, the gear-wheel H' being thus held close up to the under side of the bar C to prevent vertical play.

A small collar, g, is formed on the hollow shaft G just below the lower end of the sleeve H, to prevent said hollow shaft from rising out of the proper position while the churn is in operation.

j represents a horizontal bearing on the side of the standard D, in which is mounted the hollow shaft J, and the said shaft has the master gear-wheel K mounted thereon in position to mesh with the gear-wheels G' and H' 95 and rotate them in opposite directions. The outer side of the master gear-wheel K is provided with the square lug L, which is engaged by the socket of the crank-arm M, as most clearly shown in Fig. 3. It may sometimes 100 be found desirable to secure a band-pulley on this lug L instead of the crank-arm, and such change will involve no departure from my invention.

To the lower end of the hollow shaft G, below the end of the sleeve H, are secured the lateral arms *n n*, and to the said arms are secured the upper and lower ends of the blades 5 N N, which are twisted in reverse directions and are approximately bow-shaped. Thus as they are rotated their lower ends will tend to draw the contents of the churn-body upward, while their upper ends will direct the 10 same outward against the sides of the body.

To the lower end of the sleeve H are secured the lateral arms *o o*, which project beyond the arms *n n*, and to the extremities thereof are secured the depending blades O O, which are 15 slightly twisted, as shown, so as to draw the contents of the tub upwardly and throw them inwardly in a direction about at right angles to that given by the blades N N. This creates great agitation of the contents of the churn.

20 As before stated, both dashers N and O draw the contents of the churn from the bottom, and therefore there must be a very slight vacuum produced there which must be filled. It is filled by air, which passes down through 25 the hollow shaft. The advantage in thus admitting air to the interior of the churn at the bottom is as follows: The rapid beating of the dashers causes the air to mingle intimately with the milk, and the oxygen in the air combines 30 with the sugar in the milk to produce lactic acid, which acid produces a curdling of the milk, and consequently a rapid separation of the butter therefrom.

Having thus described my invention, I 35 claim—

1. The combination, with the churn A, of the brackets B B, secured to the sides thereof, the horizontal bar C, the operating mechanism carried by said bar, and the depending arms 40 E E, adjustably hinged at their upper ends to the extremities of the said bar C and secured at their lower ends in the said brackets B B, substantially as set forth.

2. The combination, with the churn A, of 45 the brackets B B, secured to the sides thereof and comprising the sockets *b b*, the supporting-arms *b' b'*, engaging the upper edge of the churn, and the set-screws *b²*, passed through depending ears of the brackets and bearing 50 against the sides of the churn, the horizontal bar C, the operating mechanism supported by said bar, and the arms E E, adjustably hinged at their upper ends to the extremities of the bar C and engaged at their lower ends in the 55 said brackets B B, substantially as specified.

3. The combination, with the churn A and the brackets B B on the upper edge thereof, diametrically opposite each other, of the horizontal bar C, having the longitudinal slots *c c*, 60 and the series of transverse perforations *c' c'*

in its ends communicating with the slots, the operating mechanism supported by said bar, the arms E E, engaged at their lower ends in the brackets B B, and having the series of perforations *e e* in their upper ends aligning 65 with the perforations *c'* when placed in the slots *c*, and the bolts E', passing through the said aligned perforations, substantially as and for the purposes specified.

4. The combination, with the churn A and 70 the brackets B B on the upper edge thereof, of the bar C, the standard D on the upper side thereof, provided with vertically-aligned bearings *d d'*, depending arms E E, hinged at their upper ends to the extremities of the bar 75 C and adapted to engage at their lower ends in the brackets B B, the hollow shaft G, journaled in the bearings *d d'*, the gear-wheel G' on the upper end of said shaft, the dasher N on the lower end thereof, the bracket I, secured to the lower side of the bar C and having a bearing, *i*, therein, the sleeve H, surrounding the hollow shaft G and operating in the bearing *i*, the gear-wheel H' on the upper end of said sleeve between the bracket I and 80 the under side of the bar C, the dasher O on the lower end thereof, and the master gear-wheel K, mounted in a bearing on the side of the standard and meshing with the gear-wheels G' and H', substantially as specified. 85

5. The combination, with the churn and the standard D, supported over the center thereof and provided with vertically-aligned bearings *d* and *d'*, of the hollow shaft G, journaled in the said bearings and extending to a point near 90 the bottom of the churn, the sleeve H, surrounding and operating on the said hollow shaft, gear-wheels on the upper ends of the hollow shaft G and sleeve H, the master-wheel K, meshing with the said gear-wheels to rotate 100 them in opposite directions, lateral arms *n n* on the lower end of the hollow shaft, blades N N, secured to the said arms and twisted to draw the contents of the churn upwardly and 105 outwardly, the arms *o o* on the lower end of the sleeve H, and the blades O O, secured to the extremities of the said arms, adapted to rotate around the blades N, the blades O O being twisted to draw the contents of the churn upwardly and inwardly, all constructed 110 and arranged substantially as and for the purpose specified.

In testimony that I claim the foregoing as my own I have hereto affixed my signature in presence of two witnesses.

RICHARD H. BROWNING.
